US00D910435S

(12) **United States Design Patent** (10) Patent No.: **US D910,435 S**
(45) Date of Patent: **** Feb. 16, 2021**

(54) **CONTAINER**(71) Applicant: **Kraft Foods Group Brands LLC**,
Chicago, IL (US)(72) Inventors: **Joseph C. Denison**, Chicago, IL (US);
Stephen Patrick Kennedy Dow,
Willowbrook, IL (US); **Timothy Leo**
Ridley, Sleepy Hollow, IL (US)(73) Assignee: **Kraft Foods Group Brands LLC**,
Chicago, IL (US)(**) Term: **15 Years**(21) Appl. No.: **29/683,490**(22) Filed: **Mar. 13, 2019**(51) LOC (13) Cl. .... **09-03**(52) U.S. Cl.
USPC ..... **D9/425**(58) **Field of Classification Search**USPC D7/400, 601, 608; D9/416, 417, 420,

U.S. Appl. No. 11/246,370, filed Oct. 7, 2005, Bonner.

(Continued)

Primary Examiner — Janice Patyk(74) *Attorney, Agent, or Firm* — Fitch, Even, Tabin &
Flannery LLP(57) **CLAIM**We claim the ornamental design for a container, as shown
and described.**DESCRIPTION**FIG. 1 is a top perspective view of embodiment one, of a
container, showing our new design.

FIG. 2 is a top plan view thereof.

FIG. 3 is a front view thereof, the rear view being identical.

FIG. 4 is a left side view thereof, the right side view being
identical.

FIG. 5 is a bottom view thereof.

FIG. 6 is a top perspective view of embodiment two, of a
container, showing our new design.

FIG. 7 is a top plan view thereof.

FIG. 8 is a front view thereof, the rear view being identical.

FIG. 9 is a left side view thereof, the right side view being
identical; and,

FIG. 10 is a bottom view thereof.

The broken lines in the figures illustrate the portions of the
design that form no part of the claimed design.**1 Claim, 6 Drawing Sheets**| (56)	References Cited
